UNITED STATES PATENT OFFICE.

GEORGE A. ENSIGN, OF DEFIANCE, OHIO, ASSIGNOR TO THE DEFIANCE MACHINE WORKS, OF DEFIANCE, OHIO, A CORPORATION OF OHIO.

TURNING AND BORING LATHE.

SPECIFICATION forming part of Letters Patent No. 689,071, dated December 17, 1901.

Application filed May 22, 1901. Serial No. 61,401. (No model.)

To all whom it may concern:

Be it known that I, GEORGE A. ENSIGN, a citizen of the United States, and a resident of Defiance, in the county of Defiance and State 5 of Ohio, have invented a new and Improved Turning and Boring Lathe, of which the following is a full, clear, and exact description.

The invention relates to woodworking machinery; and its object is to provide a new 10 and improved turning and boring lathe designed for rapidly and accurately producing various articles from wood and arranged to completely bore, turn, polish, and cut off the article from the stock, so that no further 15 hand-labor is required, and the article appears exceedingly sharp, clean, and smooth when leaving the lathe.

The invention consists of novel features 20 and parts and combinations of the same, as will be fully described hereinafter, and then pointed out in the claims.

A practical embodiment of the invention is represented in the accompanying drawings, forming a part of this specification, in which 25 similar characters of reference indicate corresponding parts in all the views.

Figure 1 is a perspective view of the improvement. Fig. 2 is an enlarged transverse section of the same on the line 2 2 in Fig. 1. 30 Fig. 3 is a like view of the same on the line 3 3 in Fig. 1, and Fig. 4 is a sectional side elevation of the tool-post and the finishing-tool held thereon.

On the bed A of the lathe is mounted a suitable head-stock B, carrying a spindle C, provided with driving-pulleys D and with a chuck E for engaging and holding one end of the stock F to be first acted on at its other end by a roughening-tool G, then bored by a bit 40 H, then finished by a finishing-tool I, the finished article being finally cut off the outer end of the stock by a cut-off tool J. The roughening-tool G extends through a slot K' into the mouth of a bushing K, removably held in a suitable bearing on the carriage L, the axis of the bushing coinciding with the axis of the spindle C, so that the free end of the stock F can pass through the bore of the bushing, the size of the bore conforming to 45 the largest diameter of the article to be fin-

ished. As shown in Fig. 2, the bushing is formed at its front face with a flange K², abutting against the front of the carriage L, and a set-screw K³, screwing in the latter, serves to securely hold the bushing in position. 55

A carriage L is mounted to slide longitudinally on suitable guideways A', formed on the bed A, and the movement of said carriage is manually controlled by the attendant of the lathe, and for this purpose a spindle L' is 60 journaled in suitable bearings on the carriage, and the outer end of this spindle is provided with a hand-wheel L², and the inner end carries a pinion L³ in mesh with a rack L⁴, extending longitudinally on the front of the bed 65 A, as is plainly shown in Fig. 1. When the attendant turns the hand-wheel L², the carriage L is moved longitudinally toward the head-stock B to cause the roughening-tool G to roughen the stock F at the free end thereof, the roughened portion of the stock passing through the bore of the bushing K and projecting from the right-hand side thereof, to be then engaged by the finishing-tool I for 70 turning this end of the stock into the complete article. 75

In case the article is to be bored in addition to being turned, the bit H is first moved up to bore the end of the stock previous to finishing the same by the tool I; but in case 80 the article is not to be bored then the bit H is dispensed with and a cup-shaped center is employed to engage the outer end of the stock and hold the same true during the finishing process. When the stock, however, is bored 85 by the bit, then the latter remains in position during the finishing process by the tool I, so that the stock is steadied at the outer end. The roughening-tool G is held on a tool-post G', fulcrumed at G² on the carriage L, and 90 a screw G³, screwing on said carriage, engages the bottom of the tool-post G' to permit of adjusting the tool-post and bringing the cutting edge of the roughening-tool G in proper position relatively to the stock. A 95 bolt G⁴, extending through a segmental slot G⁵ in the tool-post G', serves to fasten the latter in place after the tool-post is adjusted, as previously mentioned. A clamping-bar G⁶ engages the top of the roughening-tool, so as 100

to securely hold the same in place in the tool-post G', and a set-screw G⁷ presses the clamping-bar G⁶ for the purpose mentioned.

The finishing-tool I has a cross-section 5 throughout its length conforming to the shape of the article to be turned from the stock F, and the cutting edge of the tool is formed by beveling one end thereof in the usual manner, as is plainly indicated in Fig. 3. The 10 tool I is moved transversely through the stock, the cutting edge and the upper face being a distance from the axis of the stock, so that during the transverse movement of the tool I the stock is turned to the exact shape, it being understood that the distance the cutting 15 edge passes through the stock from the axis thereof corresponds to the diameters of the article to be finished.

The finishing-tool I is held in a tool-post N 20 and is fastened therein by set-screws N', engaging the top of the tool I, so as to press the same in contact with removable bottom pieces N², as is plainly indicated in Figs. 3 and 4. The tool-post N has its base N³ mounted to 25 slide on transverse guideways N⁴, fulcrumed at N⁵ on the front of the carriage L, and on the free end of said guideways N⁴ is arranged a yoke N⁶, engaged by a screw-rod N⁷, abutting with its lower end on the carriage L, so 30 as to hold the guideway N⁴ in a desired inclined position, so that when the tool-post N is moved transversely on the guideway the cutting edge and top of the finished tool I are the desired distance from the axis of the stock. 35 The yoke N⁶ is adapted to be locked in place on the carriage L after the desired adjustment is made by the screw N⁷, and for this purpose a bolt N⁸ is provided, screwing in the carriage L and extending through a segmental 40 slot N⁹, formed in the yoke N⁶, as is plainly shown in Figs. 2 and 3.

In order to impart the desired transverse movement to the tool-post N, the latter is provided with a rack O in mesh with a pinion O', secured on a shaft O², mounted to turn and to slide longitudinally in bearings carried by the carriage L. A handle O³ is secured on the shaft O² and is adapted to be taken hold of by the operator to enable the 45 latter to impart a turning motion to the shaft O² and to cause the pinion O' to move the rack O and tool-post N transversely to cause the tool I to engage and turn the stock, as above explained, and to return the tool I to 50 a starting position, as shown in Fig. 3. A block O⁴ is held between the pinion O' and one of the bearings for the shaft O², so as to hold the pinion O' in mesh with the rack O; but when the attendant desires to change the 55 position of the handle O³ then he releases the block O⁴ and pulls on the handle O³ to slide the shaft O² from the left to the right, and thereby move the pinion O' out of mesh with the rack O. The attendant can now 60 move the handle into a desired position and then slide the shaft O² from the right to the left to again move the pinion O' in mesh with

the rack O. The block O⁴ is then again inserted between the pinion O' and the bearing to hold the pinion in mesh with the rack. 70

The cut-off tool J is secured on a tool carrier or post P, mounted to slide vertically on bearings L⁵, secured or formed on the carriage L, and on said carrier P is arranged a pin P', extending through an elongated slot 75 P² in an arm P³, fulcrumed at P⁴ on the carriage L. (See Fig. 2.) A spring P⁵ is connected with the arm P³, so as to hold the latter and the cut-off tool J normally in an uppermost position, said spring P⁵ being connected with a screw-rod P⁶ for regulating the tension of the spring P⁵. A lever P⁷, adapted to be taken hold of by the attendant, is connected with the arm P⁸, so that upon swinging the lever P⁷ downward in a forward direction 80 against the tension of the spring P⁵ then the arm P³ by the pin P' imparts a downward sliding motion to the tool post or carrier P and moves the cut-off tool J in engagement with the stock at the end of the 85 article formed by the tool I and adjacent to the outer end of the bushing K, so that the article is cut off from the stock. When the attendant releases the pressure on the lever P⁷, then the spring P⁵ returns the several 90 parts to an uppermost dormant position. The arm P³ can also be automatically actuated from the tool-post N, and for this purpose the arm P³ is provided with an angular arm P⁸, carrying a vertical roller P⁹, adapted to be 95 engaged by a lug P¹⁰, secured to the base N³ of the tool-post N, so that when the latter is moved transversely and the tool I has finished the article then the lug P¹⁰ moves in engagement with the friction-roller P⁹ and imparts a swinging motion to the arms P⁸ and 100 P³ to slide the carrier P downward, and thereby cause the cut-off tool J to cut off the article 105 from the stock after the article has been finished by the tool I. The tail-stock center Q, carrying the bit H or cup-center, is adjustably held by a set-screw Q' in the tail-stock Q², mounted to slide on the guideway A', and on said tail-stock Q² is journaled a shaft Q³, carrying a pinion Q⁴ in mesh with the rack 110 L⁴, so that when the shaft Q³ is turned the tail-stock can be longitudinally adjusted on the guideway A' to bring the bit H or the cup-center in engagement with the end of the stock for the purpose previously mentioned. 115 A hand-wheel Q⁵ is secured on the outer end of the shaft Q³ to permit the attendant to conveniently and quickly turn the shaft Q³. 120

On the bed A, adjacent to the head-stock B, is secured a stop R for the carriage L to 125 limit the movement of the said carriage from the right to the left and prevent the roughening-tool G from moving in engagement with the chuck E.

The operation is as follows: The stock F, 130 of a desired length and diameter, is secured at one end in the chuck E, and then the attendant by turning the hand-wheel L² feeds the carriage L from the right to the left, so

that the roughening-tool G turns the stock F, the turned portion passing through the bushing K to the right-hand side thereof, and when the desired length projects beyond the bushing corresponding to that of the article then the attendant stops the feed of the carriage L, takes hold of the handle O³, and swings the same upwardly and transversely to cause the tool-post N to feed the tool I through the stock, and thereby turn the article to the desired shape. As the top face of the tool I corresponds to the shape of the finished article it is evident that after the cutting edge has dressed the stock to the shape of the article then the top surface of the tool I moves in engagement with the article, and thereby polishes and smoothes the same. The attendant then swings the handle O³ back to its previous position, so that the tool I moves out of engagement with the article, and the latter is now cut off, as previously explained, either by the operator swinging the lever P⁷ downward or the lug P¹⁰ having previously engaged the friction-roller P⁹, as described. In case the article has to be bored, then the bit H is used as previously explained, the bit remaining in position during the finishing operation by the tool I, and then the bit is run out of the article previously to cutting the article from the stock by the cut-off tool J. After the article has been cut the operator again turns the hand-wheel L² and the above-described operation is repeated.

Having thus fully described my invention, I claim as new and desire to secure by Letters Patent—

1. A lathe having a tool-post mounted to slide transversely relatively to the stock, a finishing and polishing tool carried by the tool-post and having its cutting edge and top face conforming to the shape of the article to be turned, a guideway pivoted at one end and upon which the tool-post slides, an adjusting device for the free end of the guideway, a rack on the tool-post, a pinion movable in and out of mesh with the rack, and means for operating the pinion, as set forth.

2. A lathe having a tool-post mounted to slide transversely to the stock, a finishing and polishing tool carried by the post, a guideway pivoted at one end and on which the post slides, an adjusting device for the free end of the guideway, a rack on the tool-post, a shaft mounted to slide and turn, a pinion on the shaft and meshing with the rack, a handle on the shaft for turning and sliding it, and means for locking the shaft against sliding movement, as set forth.

3. A lathe having a tool-post mounted to

slide and provided with a rack, a shaft mounted to turn and to slide and provided with a pinion meshing with the rack, and with a handle for turning and sliding it, and means for locking the shaft against sliding movement, as set forth. 65

4. A lathe having a tool-post carrying a finishing and smoothing tool and mounted to slide transversely and cause the tool to turn the stock and smooth the article turned, a sliding cut-off tool-carrier, and means adapted to be engaged by the tool-post to operate the cut-off tool, as and for the purpose set forth. 7c

5. A lathe having a tool-post mounted to slide transversely, a rack on said tool-post, a pinion in mesh with said rack, a shaft mounted to turn and to slide lengthwise and carrying said pinion, a handle on said shaft, and a removable block for insertion between the pinion and a shaft-bearing, as set forth. 75 80

6. A lathe, comprising an upper stock-spindle carrying a chuck for the stock, a carrier mounted to slide longitudinally, a stock-bushing removably held on said carrier in axial alinement with said spindle, a roughening-cutter on the carrier and extending through a slot in the bushing to the bore thereof, a tool-post mounted to slide transversely on the carrier relatively to the stock, a finishing-tool on said tool-post, a vertically-movable carrier carrying a cut-off tool for cutting off the finished article from the stock, and means adapted to be engaged by the tool-post to operate the tool-carrier, as set forth. 85 90

7. In a lathe, the combination with a transversely-movable finishing-tool carrier, of a vertically-sliding cut-off-tool carrier, and an angular arm having one member loosely connected with the cut-off-tool carrier and its other member projecting into the path of the finishing-tool carrier, as set forth. 95 100

8. In a lathe, the combination with a sliding finishing-tool post provided with an upwardly-projecting lug, of a vertically-sliding cut-off-tool carrier provided with a lateral pin, an angular pivoted arm having a slot in one member through which said pin passes, the other member of the arm extending down in the path of the lug of the tool-post, and a spring secured to said arm and to a fixed support so as to hold the said carrier in an uppermost position, as set forth. 105 110

In testimony whereof I have signed my name to this specification in the presence of two subscribing witnesses.

GEORGE A. ENSIGN.
